UNITED STATES PATENT OFFICE.

HANS CHRISTENSEN, OF SEATTLE, WASHINGTON.

TELEPHONE-INDICATOR.

1,102,719.

Specification of Letters Patent. Patented July 7, 1914.

Application filed February 13, 1913. Serial No. 748,180.

To all whom it may concern:

Be it known that I, HANS CHRISTENSEN, a citizen of the United States, residing at Seattle, in the county of King and State of Washington, have invented a new and useful Improvement in Telephone-Indicators, of which the following is a specification:

This invention relates to a device for indicating to a party calling over a telephone, or in the case of a party line to the operator at the central office the presence or absence of the party called.

It is at present the common practice to continue to ring the call bell until repeated ringing has failed to secure a response. This not only causes considerable loss of time to the party calling but in the case of a party line may unnecessarily interfere with the use of the line by other parties.

I am aware of the fact that there are a number of devices known as answer-back or return signal devices, which indicate to either the operator at the exchange or to the party calling whether a line is or is not clear, or whether a particular telephone is in working order. But while these signal devices indicate the condition of the line and also indicate that a particular telephone has been reached they do not indicate the presence of the party called.

The object of the invention is to provide a signal system which can be set by the party in whose office, store or dwelling the telephone is located. This system in the case of an individual line might be any form of signal which would be automatically sent over the line to the caller in the absence of the party called, said signal being automatically given by mechanism operated by the vibrations of the bell hammer.

In the case of a central office and of a party line the most simple form of signal would be the placing of an incandescent lamp in a normally open circuit, said circuit being rapidly closed and broken by the operation of the device. In case the party called is at home this circuit making and breaking device is inoperative, but should he leave the place where the telephone is located he will place the said device in operative position, and consequently the ring of the bell of said telephone at any time during his absence will at once through the operation of said device make and break this normally open circuit causing the signal

light at the central office to flash on and off thereby at once notifying the operator that the party is not at home, and consequently no time is lost in repeated ringings of the call bell.

In the accompanying drawings: Figure 1 is a sectional elevation of a corner portion of a telephone box, the parts being shown in operative position. Fig. 2 is a section on the line 2—2 of Fig. 1. Fig. 3 is a horizontal section on the line 3—3 of Fig. 1. Fig. 4 is a diagrammatic view illustrating the relative position of certain disks placed in the respective telephones of a four party line, said disks being in normal position. Fig. 5 is a similar view of the same disks, when one bell has been rung. Fig. 6 is a similar view showing the position of the disks when four bells have been rung.

It will be understood that the number of bells rung designates the call number of the four telephones arranged on said party line. As the interior construction of each telephone upon the line is the same, a description of one will answer for all.

In the drawings, 1 represents the telephone box, and it will be understood of course that the relative arrangement of the various parts may be changed to conform to various styles of boxes, and it will also be understood that the size of the disks, and the number of portions into which each disk is supposed to be sub-divided can vary with the number of parties upon the line. The drawings and the description hereafter given illustrate a line having four subscribers.

The usual bells 2 carried by the box are struck alternately by the vibrations of a hammer 3. These are the ordinary parts now in use. Mounted within the box are two disks 4 and 5 arranged at right angles to each other and provided with intermeshing pins 6, said pins being spaced equidistant apart, and in a four party line there will be five pins. The disk 4 is simply an operating disk designed to aid in transmitting motion from the hammer 3 to the signal controlling disk 5. To effect this motion I provide the hammer 3 with a small knocker arm 7 and a rod 8 is slidably mounted in a suitable bracket 9 and a light coil spring 10 bears at one end upon the bracket and at the other end upon a suitable collar, flange or other equivalent carried by the rod 8. This is a comparatively weak spring with inst

sufficient strength to return the bar 8 to normal position after the hammer 3 has come to rest. The bar carries a pawl 11 which normally rests against one of the pins 6 of the disk 4. Upon vibration of the hammer 3 the knocker arm 7 will strike the rod 8 throwing the same toward the disk 4 and the pawl will move the pin 6 causing rotation of the disk 4 one step, which in the case 10 of a four party line is one-fifth of a complete rotation. After the first blow of the knocker throwing the bar toward the disk 4 the tendency of the spring 10 will be to return the arm but the rapid vibration of the hammer will prevent complete return of the arm to normal position and the pawl 11 will therefore catch upon the next pin 6, thus preventing further rotation of the disk 4. When the hammer 3 comes to rest the 20 spring 10 can then move the bar 8 back to the position shown in Fig. 1, the pawl 11 lifting over the pin upon which it had caught on the return movement of the bar. The bar is therefore in position to give the 25 disk another one-fifth rotation when the bell is again rung.

As the pins 6 of the disks 4 and 5 intermesh it will be obvious that the step by step rotation of the disk 4 will also be imparted 30 to the disk 5. The disk 5 has a segment cut therefrom as indicated at 12, said segment comprising substantially one-fifth of the disk indicating one step in its rotation. The hammer 3 carries an arm 13 from which depends a pendulum 14 having at its lower end a contact block 15. The arm 13 may be insulated in any desired manner from the hammer 3. Leading into the telephone box are the two wires 14^a of a signal circuit, said 40 circuit extending to the central office at which point any form of signal device, as for example an electric light may be inserted in said circuit. As the use of such signal light in a circuit is well known it has not 45 been considered necessary to illustrate the manner of arranging the said light in the circuit. This circuit 14^a is normally open and the wires or other conductors forming the circuit within the telephone box are 50 spaced apart and terminate adjacent the side of the disk 5 opposite the hammer 3.

Any suitable form of operating rod 15^a is connected to one member of the circuit, said 55 rod 15^a passing upwardly through the telephone box whereby one of said circuit members may be drawn upwardly out of parallel relation with the other member, and a suitable bracket 16 or other device may be employed for holding the rod 15^a in elevated 60 position. The disk 5 is provided with numerals upon its periphery, said numerals running from zero to 4.

In the diagrammatic view I have placed these numerals upon the sides of the disks 65 in order to more clearly show the operation.

These numerals are visible through a sight opening 17 formed in the top of the telephone box and normally the numeral zero will appear through said sight opening in all four of the telephones. When a party 70 is called the vibrations of the hammer 3 will be transmitted through the arm 13 to the pendulum 14 which will swing through the cut out segmental portion of the disk 5 so that the contact plate 15 will strike the ends of the members of the circuit 14. Each contact made by the swinging pendulum will therefore complete the circuit through the signal device at the desk of the operator. If such signal is arranged to indicate the absence of the subscriber, which is the preferred form, the operator will upon receiving the signal cease ringing and at once notify the calling party that the subscriber called cannot be reached. But upon the return of the party he will lift the rod 15 into the position shown in dotted lines in Fig. 1, thereby rendering the signal device inoperative since the contact pin 15 would now strike but one of the conductor members, 80 and consequently the circuit would not be completed.

Referring to Figs. 4, 5 and 6 I have shown therein the normal second and fourth positions of the various disks 5. It will be noted that in their normal positions the disks in all telephones on the line will have a solid portion at the top, which will be termed the zero position and the cipher will appear upon the periphery of the disk through the sight opening. These disks turn from right to left, and the open portion will upon the ringing of one bell be brought into position in the telephone of the subscriber whose call is one ring so that the pendulum will swing through said open position and engage the circuit members 14^a. Of course if said subscriber is home the circuit will not be completed but if he should be absent the operator will be notified of that fact as above explained. If the call is for the fourth party upon the line whose signal call is four rings, the disks in all of the telephones upon the line will upon the fourth ring occupy the position shown in Fig. 6. After a subscriber has been reached it is necessary for the operator to again ring a sufficient number of times to clear the line or in other words to return the disks to normal position. For example if the subscriber 100 whose signal call is four rings has been called up, the operator will either after conversation has been finished or it has been ascertained that said subscriber is not at home, give one more ring which will return 105 all of the disks to the position shown in Fig. 4. If the party whose signal call is one ring has been called and the disks are in the position shown in Fig. 5 the operator will ring four times to again bring the 110 115 120 125 130

disks back to normal position as shown in Fig. 4.

What I claim is:—

1. In a telephone, the combination with a vibrating arm of a signal device, a rotatable disk having a cut-out portion a normally open circuit, and a freely swinging pendulum supported from said vibrating arm and adapted to swing through the opening in said disk and bridge the gap in said circuit.

2. The combination with a telephone having a vibrating call signal member, of a disk having a portion removed therefrom, a circuit making and breaking device supported from said vibrating member and adapted to swing through the cut out portion of said disk when said disk is in a predetermined position, and means operated by movement of said vibrating member for rotating said disk.

3. In a telephone box a vibrating signal member, a pendulum supported therefrom, a contact block carried by the pendulum, elec-

tric conductors spaced apart and adapted to be simultaneously engaged by said block 25 upon swinging of the pendulum, and means for moving one of said conductors into inoperative position.

4. The combination with a vibrating member of a signal device, a swinging pendulum operatively connected to said member, a normally open circuit adapted to be completed and broken by the swinging of said pendulum, a rotatable disk interposed between the members of said circuit and 30 said pendulum, said disk having a cut-out portion, and means operatively connected to said vibrating member for moving the cut-out portion of said disk into alignment with the said pendulum and circuit members upon the sounding of said signal devices a predetermined number of times.

HANS CHRISTENSEN.
